Primary Examiner—Stella M Reid*Assistant Examiner*—Elizabeth J Oswecki(74) *Attorney, Agent, or Firm*—Marshall, Gerstein & Borun LLP; Richard M. LaBarge(57) **CLAIM**

The ornamental design for a bottle, as shown and described.

DESCRIPTION

FIG. 1 is front and bottom isometric view of a bottle showing the new design.

FIG. 2 is a front and top isometric view of the bottle.

FIG. 3 is front elevation view of the bottle.

FIG. 4 is a right-side elevation view of the bottle. The left-side elevation is identical to this view.

FIG. 5 is a rear elevation view of the bottle.

FIG. 6 is a bottom plan view of the bottle; and,

FIG. 7 is a top plan view of the bottle.

The broken line showings of threads and the parts of the bottom of the bottle is for the purposes of illustrating parts of the bottle and forms no part of the claimed design.
